212,325

COMBINED CARRIAGE AND INFANT SEAT

Stanley F. Korol, Everett, Pa., assignor to Hedstrom
Union Company, Bedford, Pa.

Filed Jan. 30, 1968, Ser. No. 10,367

Term of patent 14 years

(Cl. D14—14)

FIG. 1

FIG. 2

FIG. 3

FIG. 5

FIG. 4

FIG. 6

FIG. 1 is a perspective view of a combined carriage and infant seat embodying my new design with the separable carriage body in its upright position;

FIG. 2 is a top view thereof;

FIG. 3 is a rear view thereof;

FIG. 4 is a front view thereof;

FIG. 5 is a perspective view thereof with the body in its reclined position; and

FIG. 6 is a perspective view thereof in its infant seat position separate from the carriage frame.

The hidden side of the carriage in FIGS. 1, 5 and 6 is substantially the same as the visible side.

The dominant features of my design reside in the portions shown in full lines.

I claim:

The ornamental design for a combined carriage and infant seat, substantially as shown and described.
